UNITED STATES PATENT OFFICE.

ERNEST H. JACOBS, OF SCHENECTADY, NEW YORK, ASSIGNOR TO GENERAL ELECTRIC COMPANY, A CORPORATION OF NEW YORK.

ELECTRIC SWITCH MECHANISM.

1,297,174.

Specification of Letters Patent. Patented Mar. 11, 1919.

Application filed April 29, 1915. Serial No. 24,782.

To all whom it may concern:

Be it known that I, ERNEST H. JACOBS, a citizen of the United States, residing at Schenectady, county of Schenectady, State 5 of New York, have invented certain new and useful Improvements in Electric Switch Mechanism, of which the following is a specification.

My invention relates to electric switches 10 and more especially to the mechanisms for automatically operating such switches.

The object of my invention is to improve in general the operating mechanism of electric switches and more particularly to provide an improved form of tripping means 15 for electric switches. To this end I provide a tripping device comprising a relay mounted independent of the switch with a winding connected directly to the circuit through the switch, the relay being operatively related to means directly mounted on the switch for tripping the switch instantaneously or with a time lag upon the occurrence of a pre-determined overload. The current and time 20 adjustments for the tripping device are insulated from the relay and are adapted to be easily, safely and accurately made without interfering with the operation of the switch.

The novel features which I believe to be 30 characteristic of my invention will be definitely indicated in the claims appended hereto; the features of construction and mode of operation will be identified by reference to the accompanying drawings which 35 show the preferred embodiments of my invention and in which:—

Figure 1 is a side elevation, partly in section, of an oil switch embodying the novel 40 features of my invention; Fig. 2 is a perspective view showing more in detail, the operating mechanism of the switch embodying my improved type of tripping device; Fig. 45 3 is a front elevation, partly in section, of a portion of my tripping device and Fig. 4 is another form of the tripping device adapted for the remote control of electric switches.

Referring to the drawings and more especially to Fig. 1, I have shown for purposes of illustration, the features of my invention embodied in a three phase oil switch having three poles or switch units just alike, only two being shown. Each pole or unit comprises an oil vessel 1, having mounted thereon insulators 2 carrying the terminals and

fixed contacts of the switch. Mounted between the bushings or insulators 2 of each pole, is the actuating arms 3 of the operating mechanism for the switch, to which arms are connected insulating rods 4 carrying the movable coöperating bridging contacts of 55 the switch. The actuating arms 3 for the three poles of the switch or for each of the switch units are arranged to move rods 4 and hence the movable contacts, in a straight line, by means of parallel motion link mechanisms 60 5, all the parallel motion mechanisms being interconnected by a rod 6 so as to move simultaneously.

The operating mechanism, suitably mounted at one end of the switch, controls the 70 movement of the parallel motion mechanisms 5 and rod 6 to cause the opening and closing of the switch. I do not claim, in this application, the operating mechanism *per se*, as this mechanism is described and claimed in 75 my copending application Ser. No. 840,501. This operating mechanism which is of the automatically operated, trip-free-from-the-handle or control mechanism type, comprises the parallel motion link mechanism 5 for 80 operating the movable contacts of the switch in a straight line. This parallel motion mechanism is actuated by a toggle comprising lever 7 and the bell crank lever 8. Mounted on a shaft 9 is a double bell crank 85 operating lever 10 having bifurcated arms 11 connected by the rod 12 and connected also by rod 13 upon which is mounted the bell crank lever 8 of the actuating toggle. Connected between one end of the bell crank 90 lever 8 of the actuating toggle and arms 11 of the operating lever 10, is a collapsible locking toggle comprising toggle links 14 and 15. A latching member 16 pivotally mounted on rod 12 with toggle link 14, co- 95 operates with toggle link 15 to normally hold the locking toggle in locked or rigid position. Connected at the other end of operating lever 10, is an operating toggle comprising members 17 and 18, the member 100 18 being mounted on the operating shaft 19.

The latching member 16 is so mounted that it is normally in latching position, being moved into unlatching or releasing position by its engagement with the tripping arm or 105 member 20. This tripping arm 20 is mounted between the arms of member 21, both member 21 and the tripping arm 20 being.

pivotedly mounted on bearing 22. The tripping arm 20 also carries a boss or offset portion 23 which coöperates, in a manner to be described, with a pawl 24 operatively related to the operating shaft 19.

In Fig. 2 the operating mechanism for the switch is shown in switch closing position. It will be apparent from the following description that this mechanism trips-free-
10 from-the-handle whether the switch is opened by hand or is opened automatically. A handle for the manual operation of the switch is adapted to be applied to the operating shaft 19. When the switch is man-
15 ually opened, the shaft 19 is rotated in the direction shown by the arrow, the shaft moving the pawl 24 into engagement with the boss 23 which causes the tripping arm 20 to move into tripping engagement with
20 latching member 16. The latching member is thus moved into releasing position and, the locking toggle 14—15 immediately collapses to break the rigid connection between the operating lever 10 and the actuating tog-
25 gle 7—8. The actuating toggle 7—8 collapses suddenly, independent of the operating lever 10, and releases the parallel motion mecha-
nism 5 and hence the movable contacts of the switch move with a quick action, into
30 switch opening position. The arm 25 connected to the parallel motion mechanism op-
erates to move the rod 6 which connects the arms 25 for the other poles of the switch and thus opens all the poles of the switch
35 simultaneously. For closing the switch, it will be apparent that the shaft 19 must be rotated until the locking toggle 14—15 is again straightened and moved into locking position, in which position it is held by the
40 latching member 16. As the actuating tog-
gle 7—8 is then rigidly connected to the oper-
ating lever 10, the rotation of the shaft 19 into switch closing direction, is directly
45 communicated through the operating toggle
17—18, operating lever 10 and locking toggle
14—15 to the actuating toggle 7—8 and par-
allel motion mechanisms 5 to close the
switch.

For automatically tripping the operating
50 mechanism to open the switch, I provide my novel tripping mechanism which operates to automatically raise the tripping arm 20 into tripping engagement with the latching member 16, in response to a current flow
55 through the switch above a predetermined amount. The mechanism operates to move the tripping arm 20 into tripping position preferably with a time interval but it can be made to operate instantaneously if de-
60 sired.

My improved type of tripping mechanism is of the series-trip type and comprises a relay 26 mounted independently of the switch and carried upon an insulator, the relay hav-
65 ing an energizing winding connected in

series with the circuit through the switch. This relay differs from those previously used in that no time or overload adjustments are made upon the relay itself, all such adjustments being made by means separately 70 mounted on the switch, insulated from the relay and thereby maintained always at ground potential. By this construction I can adjust the time and current settings of my relay without interrupting the operation 75 of the switch.

The relay 26 has pivotally related to its armature a lever arm 27 to which is connected a tripping rod 28 of insulating ma-
terial. The connection between the rod 28 80 and lever arm 27 is preferably a universal joint thus permitting the location of the relay to suit local conditions. The rod 28 may be inclined 15 degrees from the vertical without affecting the accuracy of the mecha-
85 nism. The relay 26 is designed to respond to conditions of overload upon the circuit through the switch, and in so responding the tripping rod 28 is raised by the lever arm 27 to cause the movement of the tripping 90 arm 20 into tripping engagement with latching member 16 in a manner to be described. For moving the tripping arm 20 automatically in response to the relay 26, I provide the member 21 pivotally mounted upon the 95 same shaft 22 with the tripping arm 20. This member 21 is moved into and out of tripping engagement with arm 20 by means of a bell crank lever or actuator arm 30 loosely mounted on a shaft 31, one end of the bell crank lever being connected to mem-
ber 21 by links 29 while the other end of the lever 30 is connected to a rod 32 to which the corresponding levers 30 for the other poles of the switch are connected. As the 100 levers 30 are interconnected by the rod 32, all the levers 30 are operated simultaneously.

The time limit means for my tripping de-
vice is also connected to the same end of the actuator arm 30 as member 21 and com-
110 prises a dash pot 33 secured to a support 34 on the switch, the plunger of the dash pot being secured to a bar 35 connected by links 36 to the actuator arm 30. The operation and novel construction of this time limit 115 means will be described more in detail hereinafter. It is apparent from the descrip-
tion given that when the arm 30 is actuated to move the member 21 to tripping position, it has to move under the action of the time 120 limit means or dash pot 33. If a time limit is not desired, this dash pot can be readily removed or disconnected from the arm 30 without impairing the operating efficiency of the rest of the tripping device.

To actuate the arm 30, I provide a mem-
ber or finger 37 which is adjustably mounted on the shaft 31 and which engages one or the other arms of the bell crank lever 30 to move the lever into and out of switch trip-
125 130

ping position. The finger 37 and shaft 31 are actuated in response to the relay 26 through the actuation of a current adjusting or overload setting means for the device 5 which comprises a rotatably mounted frame or yoke 38 eccentrically pivoted on one end of the shaft 31 and in direct connection with but insulated from the relay armature 27 by the insulating rod 28. The rod 28, which 10 is pivotally connected to the yoke 38 near one end thereof, in moving in response to the relay 26, rotates the yoke 38, which in turn rotates shaft 31 and causes finger 37 to actuate the actuator arm 30.

15 The yoke 38 of the current controlling or adjusting means has a graduated scale beam 39 upon which is slidably or adjustably mounted a carriage 40 carrying a weight 41 suspended therefrom. By means of an adjusting screw 42, the carriage and weight can be positioned at any point along the scale beam. By having the yoke 38 eccentrically pivoted on the shaft 31 I can adjust my current controlling means readily 20 by positioning the weight 41. In the construction shown, by varying the position of the weight 41, the moment of the force necessary to rotate the yoke 38 is increased or decreased, that is, the force required to rotate the yoke 38 is dependent upon the position of the weight 41. The greatest pull therefore, required by the lever arm 27 to rotate the yoke 38 and shaft 31 is when the weight is at the extreme end of the frame 25 38 toward the point of connection of rod 28. For calibration, a series of graduations are made upon the scale beam 39 which correspond to settings of the weight for certain predetermined overloads. By so adjusting 30 the position of the weight 41 along the scale beam 39 a certain definite pull is required by the lever arm 27 to rotate the shaft 31 and move the arm lever 30 into switch tripping position which pull is proportional to a predetermined current flow through the relay 26. It will be understood from the construction so far described, that the relay mechanism for each unit of my switch corresponding to one pole or to one phase can 35 be operated independently to trip the switch open. The occurrence of an overload therefore above a predetermined amount on any phase of the circuit through the switch, operates the series relay of the switch unit corresponding to that phase and through its rod 28 rotates its yoke 38, and actuates its finger 37 to move its lever 30 and thereby communicate the movement, by means of rod 32, to the mechanism for tripping the switch.

40 Referring now more specifically to the time limit means, best shown in Fig. 3, the dash pot 33 partially filled with oil is attached to the support 34 by a screw head mounted on the cover of the dash pot through 45 which passes the hollow or tubular plunger or piston rod 43. This plunger or piston rod has a screw headed top by means of which the rod is secured to the bar 35 and is rendered movable thereby in response to the actuation of actuator arm 30. The other end 50 of the rod 43 is threaded into a piston 44 containing holes or openings 45 in the head thereof, concentrically arranged around a central opening 46. The opening 46 has a conical bore and communicates with the tubular rod 43. Through the threaded portion of the piston 44 is a small opening which is adapted to register with a similar opening through the threaded portion of the rod 43 to form a relief valve or passage 47 between the tubular rod 43 and the oil above the piston 44. By screwing the rod 43 up or down, the diameter of the passage 47 can be varied and the amount of oil flowing through the passage, regulated. This passage or valve 55 forms the only means of escape of the oil except through the clearance space of the piston, when the oil is subjected to pressure due to the rise of the piston. A lock nut 48 provides a means for holding the adjustment 60 of the valve 47 at any desired point and also serves to limit the movement of the annular ring or piston valve 49 which covers the openings 45 in the piston. This valve 49 performs the usual function of preventing 65 the passage of oil through the openings 45 when the plunger is raised and allowing the free passage of the oil when the piston falls.

70 With this dash pot structure, I incorporate my novel time calibrating device for easily 75 and accurately adjusting the time setting of the dash pot from the outside without interrupting the operation of the dash pot. It is well known that the time required by the piston 44 to rise under the pull of the piston rod 43, is determined by the rate of flow of the oil from one side of piston to the other. In my device when the piston moves upward, the only passage for the oil is by means of the by-pass to the valve 49 through the relief 80 valve 47 into the tubular rod 43 and thence through the central opening or needle valve 46. This passage or by-pass has two adjustments, first for regulating the opening of the valve 47 which is the rough time adjustment, and second by a fine adjustment comprising a rod 50 threaded through the screw headed top of tubular rod 43 and terminating at its lower end in a conical portion 85 which is adapted to coöperate with the conical opening 46 to form a needle valve. By screwing the rod 50 up and down, the opening 46 can be very easily regulated and the time adjustment for the dash pot accurately controlled. A lock nut 51 holds the rod 50 in 90 any desired position. It is therefore apparent that with one setting of the valve 47 the valve 46 can be easily controlled while the dash pot is upon the switch to give a wide variation of time limit values.

From the foregoing description the advantages of my novel tripping mechanism will be readily understood. The position of the weight 41 is adjusted for the occurrence 5 of the predetermined overload desired to operate the switch and the rod 50 set to the time limit desired before the switch is finally tripped open, all these adjustments being made quickly and easily upon the switch 10 itself at ground potential and without interrupting the operation of the switch. With current and time adjustments made, the current through the relay 26 must reach the predetermined excess amount before sufficient pull is exerted on the armature 27 to rotate the yoke 38. When the pull of the relay 26 is sufficient, the yoke 38 is rotated, the shaft 31 rotated and finger 37 engages and actuates the actuator arm 30. Arm 30 in 15 moving, raises the member 21 under the delayed action of the dash pot 33 and should the overload exist for the predetermined time, the member 21 raises the tripping arm 20 into tripping engagement with the latching member 16 to trip the switch open. 25

If it is desired to trip the switch by remote control, I embody the novel features of my invention in a device such as shown in Fig. 4 which consists in mounting the current adjusting or overload setting means and the time limit means on a bracket 52 which can be located at any convenient point below the series relay 26. The yoke 38 is connected to the relay by the rod 28 and is operated in the 30 same manner as has already been described except that finger 37 is removed and a lever 35 53 is substituted for the bell crank lever 30 which is fixed on the shaft operated by the yoke 38. The yoke also carries a contact arm 40 54 which is adapted to engage, the contacts 55 mounted side by side on the bracket 51, to close an auxiliary tripping circuit for the switch.

My invention may be embodied in other 45 forms than that shown and described and I, therefore, do not wish to be restricted to the precise combination shown but intend to cover by the appended claims all changes and modifications which are within the scope of 50 my invention and will be apparent to those skilled in the art.

What I claim as new and desire to secure by Letters Patent of the United States, is:—

1. An electric switch comprising an operating mechanism adapted to be automatically tripped, an actuator arm for moving said operating mechanism into tripping position, a relay responsive to current through said switch for controlling said actuator arm, current adjusting means connected intermediate said actuator arm and said relay for holding said relay inoperative until the current through said relay exceeds a predetermined amount, time adjusting means connected intermediate said actuator arm and said oper-

ating mechanism for causing the movement of said actuator arm with a delayed action, and means for maintaining both said current and time adjusting means always at ground potential. 70

2. An electric switch comprising an operating mechanism adapted to be automatically tripped, an actuator arm for moving said operating mechanism into tripping position, a relay responsive to current through said switch for controlling said actuator arm, current adjusting means connected intermediate said actuator arm and said relay for holding said relay unresponsive to current through the switch below a predetermined 75 amount, time adjusting means connected intermediate said actuator arm and said operating mechanism for causing said actuator arm to move with a delayed action, and means whereby said current and time adjusting means can be adjusted while the switch is closed. 80

3. An electric switch comprising an operating mechanism adapted to be automatically tripped, a relay connected in series with the 90 circuit through the switch, current adjusting means for said relay mounted on the switch, an insulating rod connecting said relay to said current adjusting means, an actuator arm actuated in response to movement of said 95 current adjusting means to cause the tripping of said operating mechanism, and a time adjusting means for said relay operatively related to said actuator arm for causing the movement of said arm with a delayed 100 action. 100

4. In a tripping device for an electric switch, the combination with a relay independently mounted and connected in series with the circuit through the switch, of an 105 actuator arm carried by the switch and movable in response to said relay into switch tripping position, current adjusting means for said relay carried by the switch and operatively related to said actuator arm for 110 preventing the operation of said relay until the current through the relay exceeds a predetermined amount, an insulating connection between said adjusting means and said relay, and time limit means for said relay 115 operatively related to said actuator arm to prevent the movement of said arm into switch tripping position until after a predetermined time. 115

5. The combination with the operating 120 mechanism of an electric switch, of a device for automatically tripping said operating mechanism to open the switch comprising, a relay connected in series with the circuit through the switch, means insulated from 125 said relay and mounted on the switch for controlling the current setting of said relay, an actuator arm movable by said means into switch tripping position, and means operatively related to said actuator arm for caus- 130

ing said arm to move into switch tripping position a predetermined time after said relay is actuated.

6. In combination with the operating mechanism of an electric switch having a tripping member therefor, an actuator arm mounted on the switch and adapted when actuated to move said tripping member into switch tripping position, a series connected relay mounted independently of the switch for moving said actuator arm in response to a predetermined overload on the circuit through the switch, overload setting means mounted on the switch and insulated from said relay for preventing the actuation of said actuator arm upon overloads below said predetermined amount, and retarding means separately mounted on the switch and operatively related to said actuator arm to cause the movement of said tripping member into tripping position with a time lag.

7. An electric switch comprising an operating mechanism adapted to be automatically tripped, a member movable into switch tripping position, an actuator arm for moving said mechanism into tripping position, a relay mounted independent of the switch and responsive to current conditions through the switch for operating said actuator arm, current adjusting means mounted on the switch and operatively related to said actuator arm for holding said relay inoperative until the current through the relay exceeds a predetermined amount, and means for maintaining said current adjusting means always at ground potential.

8. A tripping device for electric switches comprising a relay mounted independent of said switch and connected in series with the circuit through the switch, means operative in response to said relay for moving said switch into tripping position, and independent time and current controlling means for said relay separately mounted on said switch, and means whereby both said time and current controlling means may be adjusted independent of the position of the switch.

9. A tripping device for electric switches comprising a relay mounted independent of said switch and connected in series with the circuit through the switch, means operative in response to the actuation of said relay for tripping said switch open, current controlling means for said relay mounted on said switch, intermediate said first mentioned means and said relay, and an insulating connection between said relay and said controlling means.

10. A tripping mechanism for an electric switch comprising a member movable into switch tripping position, an actuating shaft, an actuator arm loosely mounted on said shaft and operatively related to said trip-

ping member, a member mounted on said shaft to engage said actuator arm in response to rotation of said shaft, a relay mounted independent of said switch and connected in series with the circuit through the switch, a yoke eccentrically pivoted on said shaft and adapted to rotate said shaft, an insulating rod connecting said relay to a point on said yoke eccentric to the pivot of said yoke, and an adjustably positioned weight carried by said yoke for varying the moment of the force necessary to move the yoke.

11. The combination with the operating mechanism of an electric switch adapted to be automatically tripped, of mechanism for tripping said operating mechanism comprising, an independently mounted relay connected in series with the circuit through the switch, means mounted on the switch and insulated from said relay for controlling the operation of said relay, an actuator arm operated by said means, a member movable by said actuator arm into position to trip said operating mechanism, and calibrating means for rendering said controlling means operative to hold said relay unresponsive to current through said switch below a predetermined amount, said controlling means being maintained always at ground potential.

12. The combination with an electric switch having an automatically tripped operating mechanism, of a tripping device for said mechanism comprising a series-connected relay mounted independent of the switch, current controlling means for said relay having an eccentrically pivoted yoke rotatably mounted on said switch, and a weight adjustably positioned on said yoke for varying the moment of the force necessary to rotate said yoke about its pivot, an insulating rod connecting said yoke to said relay, a shaft actuated by the rotation of said yoke, an actuator arm movable by the rotation of said shaft, and a member movable by said actuator arm into position to trip said operating mechanism.

13. The combination with an electric switch having an automatically tripped operating mechanism, of a tripping device of said mechanism comprising, a series-connected relay mounted independent of said switch, a yoke member eccentrically mounted on said switch to rotate about a fixed pivot, an insulating rod connected between said yoke and said relay for causing the rotation of said yoke in response to the action of said relay, an actuator arm movable in response to the rotation of said yoke, a member movable by said actuator arm into position to trip said operating mechanism, and an adjustably positioned weight carried by said yoke for holding said relay inoperative to rotate said yoke while the cur-

rent flow through said relay is below a predetermined amount.

14. The combination with the operating mechanism of an electric switch, of an automatic tripping mechanism therefor comprising, a relay mounted independent of the switch and connected in series with the circuit through the switch, current controlling means for said relay including, a rotatable yoke eccentrically pivoted on said switch, an insulating rod for rotating said yoke in response to said relay, and means operatively related to said yoke for varying the moment of the force necessary to rotate said yoke, and an actuator arm movable in response to the rotation of said yoke into switch tripping position.

15. The combination with the operating mechanism of an electric switch, of an automatic tripping mechanism therefor comprising, a relay mounted independent of the switch and connected in series with the circuit through the switch, current setting means for controlling the operation of said relay including, a rotatable yoke eccentrically pivoted on said switch, an insulating rod for rotating said yoke in response to said relay, and means operatively related to said yoke for varying the moment of the force necessary to rotate said yoke, an actuator arm movable in response to rotation of said yoke into switch tripping position, and time limit means for controlling the movement of said actuator arm into switch tripping position consisting of a dash pot, a piston for said dash pot movable by said actuator arm, and means mounted outside said dash pot for regulating the upward movement of said piston.

16. The combination with the operating mechanism of an electric switch, of an automatic tripping mechanism therefor, comprising a relay mounted independent of the switch and connected in series with the circuit through the switch, current setting means for controlling the operation of said relay, including, a rotatable yoke eccentrically pivoted on said switch, an insulating rod for rotating said yoke in response to said relay, and means operatively related to said yoke for varying the moment of the force necessary to rotate said yoke, an actuator arm movable in response to rotation of said yoke into switch tripping position, retarding means operatively related to said actuator arm for causing the movement of said arm into tripping position within a predetermined time and means for regulating said retarding means without interrupting the operation thereof.

17. The combination with the operating mechanism of an electric switch, of latching means for holding said mechanism in switch closing position, a member movable into a position to release said latching

means, an actuator arm for moving said member, a retarding means simultaneously movable by said actuator arm whereby said member moves with a delayed action, an electroresponsive means for moving said actuator arm, and a current adjusting means for said electroresponsive means through the agency of which said actuator arm is movable.

18. The combination with the operating mechanism of an electric switch, of latching means for holding said mechanism in switch closing position, a tripping member movable into a position to release said latching means, a current responsive relay mounted independently of said switch for moving said tripping member, means mounted on the switch for holding said relay inoperative until the current through said relay exceeds a predetermined amount, an insulating connection between said relay and said means, and means operative in response to the movement of said relay to cause said tripping member to be operated with a delayed action.

19. The combination with the operating mechanism of an electric switch, of latching means for holding said mechanism in switch closing position, a member movable into a position to release said latching means, an independently mounted series relay, current and time adjusting means for said relay mounted on the switch and adjustable while said switch is either opened or closed, and means for maintaining said adjusting means always at ground potential.

20. The combination with the operating mechanism of an electric switch adapted to be latched in switch closing position, of a member movable into a position to release said mechanism, a relay connected in series with the circuit through the switch and mounted independently of said switch, means carried by the switch for controlling the current setting of said relay and for causing said relay to operate with a delayed action, and means for insulating said first mentioned means from said relay.

21. The combination with the operating mechanism of an electric switch adapted to be latched in switch closing position, of a member movable into a position to release said mechanism, a relay connected in series with the circuit through the switch and mounted independently of said switch, an armature movable by said relay, means carried by said switch for holding said armature inoperative until the current through said relay exceeds a predetermined amount, an insulating connection between said armature and said means, a tripping member movable in response to movement of said means, and means operatively related to said tripping member for causing its movement to take place with a delayed action.

22. The combination with the operating mechanism of an electric switch adapted to be latched in switch closing position, a member movable into a position to release said mechanism, an arm for moving said member, electroresponsive means for moving said arm, means for causing said arm to move with a delayed action, and means intermediate said electroresponsive means 5 and said arm for holding said arm inoperative until the existence of predetermined conditions in said relay.

23. The combination with the operating mechanism of an electric switch adapted to 10 be latched in switch closing position, a 15

member movable into a position to release said mechanism, a current responsive relay mounted independently of said switch, means carried by said switch and movable by said relay when the current to said relay exceeds a predetermined amount, a tripping member movable in response to said means into a position to trip said operating member, and a second means carried by said switch and movable with said tripping member to cause said member to move with a time relay. 20 25

In witness whereof, I have hereunto set my hand this 27th day of April, 1915.

ERNEST H. JACOBS.
